UNITED STATES PATENT OFFICE.

EDGAR C. LITCHFIELD AND CLARENCE C. HERMANN, OF WATERLOO, IOWA; SAID HERMANN ASSIGNOR TO SAID LITCHFIELD.

FRONT AXLE.

Application filed March 26, 1923. Serial No. 627,623.

The present invention relates to vehicles of the type that are provided with tongues or poles by which they may be drawn about and has for its object, specifically considered, 5 to improve the construction of the front ends of such vehicles so as to secure great strength, make steering easy, provide capacity for adjustment, both initially and after wear takes place, and confine the stresses imposed on the 10 front axles to those due to supporting the overlying loads.

In carrying out our invention we support the front wheels on spindles capable of swinging about vertical axes in the vicinity 15 of their inner ends. The front axle is therefore not required to swing bodily for steering purposes and is therefore relieved of the stresses to which the ordinary front axle is subjected by the act of swinging it bodily 20 about a vertical axis passing through the middle thereof, during the process of steering. Viewed in one of its aspects, our invention has for its object so to associate the pole and steering devices with the front wheels 25 and the frame of the vehicle body that the front axle will be relieved from the draft stresses that must be transmitted from the pole to the frame of the vehicle body in order to move the vehicle.

30 Viewed in another of its aspects our invention may be said to have for its object to produce a novel and effective adjustable tie between the vehicle frame members in the vicinity of the front and rear axles so as to 35 guard against any possibility of the front pulling out from beneath the vehicle body.

The various features of novelty whereby 40 our invention is characterized will herein-after be pointed out with particularity in the claims; but for a full understanding of our invention and of its objects and advantages, reference may be had to the following detailed description taken in connection with the accompanying drawings, wherein:

45 Figure 1 is a side view of a manure spreader embodying our invention;

Fig. 2 is a vertical section on a larger scale than Fig. 1 through the front sill, axle and draft and steering device;

50 Fig. 3 is a front elevation of the spreader on a larger scale than Fig. 1, the pole and the means for connecting it to the steering arm being omitted;

Fig. 4 is a horizontal section taken above 55 the front sill and looking down, one front

wheel being omitted and a portion of the support for the pole being shown in section;

Fig. 5 is a view, similar to Fig. 4 but on a larger scale, of the inner end of the pole and its support;

Fig. 6 is a plan view of the clevis connecting the inner ends of the steering rods together, the inner ends of said rods also being shown;

Fig. 7 is a perspective view of one of the bearing cones in the draft appliances; and

Fig. 8 is a plan view, on a reduced scale, of the front and rear sills and the tie-rod connection between the same.

Referring to the drawings, 1 represents a 70 wagon box, at the front end of which is a transverse metal sill 2 having the ends bent up, as indicated at 3, 3, to form a U-shaped structure, the arms of which form the front vertical corner posts of the vehicle body. 75 The sill with its arms may have any desired cross section, but we prefer to form it out of a channel iron bent so that the trough of the channel lies on the outer side. Directly below the front sill is the front axle conveniently made out of two parallel angle irons 4, 4, so disposed that each has one of its flanges arranged vertically, while the other flange of one extends forwardly and the second flange of the other extends toward the 80 rear. At each end of the axle is fixed a bearing block 5; these blocks being conveniently fitted between the vertical flanges of the two angle irons and held in place by means of bolts 6 passing through said flanges and 85 through the blocks. Fitted into the trough of the sill, at the middle, is a metal bolster 7 having pedestals 8, 8 extending down between the two axle members. The pedestals are provided with vertically elongated slots 90 9 extending through the same, and there are bolts 10 passing through the vertical flanges of the axle angle irons and through the slots in the pedestals. The bolts 10 are surrounded by suitable sleeves or bushings 11 fitting 100 between the vertical flanges of the angle irons and serving as spacers to prevent the pedestals from being gripped tightly between the angle irons, and serving also as members to take the wear which would 105 otherwise come on the bolts as the pedestals move up and down relatively to the axle. The sill is provided with downwardly-projecting brackets 12, 12 bolted thereto near the ends, these brackets fitting loosely be-

110

tween the two angle irons of the axle and serving to maintain the sill in the same vertical plane as the axle, even though there be relative vertical movements between the sill and the axle in that plane.

Each front wheel 13 is supported on a spindle 14 projecting horizontally from a spindle body 15, which is also provided with a vertical journal or spindle 16 rotatably fitted in one of the bearing blocks 5. Each spindle body is also provided with a forwardly-projecting arm 17 integral therewith or fixed thereto. The outer ends of the two arms 17 are connected together by two tie rods 18, 18, each of which may conveniently have one end bent downwardly, as indicated at 19, and passed through a hole in the outer end of the corresponding arm 17 so as to form a hinge connection; while the inner ends of the rods may be adjustably connected, independently of each other, to a suitable clevis 20. In the arrangement shown, the clevis is in the form of an inverted U, each tie rod passing through one of the arms of the U and being provided with nuts 21 and 22 engaging with opposite sides of such arm. It will be seen that by adjusting the nuts on either tie rod, the effective length of that rod may be varied, and therefore the positions of the front wheels relatively to each other may be varied. The clevis is attached, by means of a bolt 26 or otherwise, to the front end of a steering arm 25, the rear end of which is pivoted to the front sill of the vehicle at the center of the latter so as to be capable of swinging about a vertical axis. It will therefore be seen that when the steering arm is moved toward the right or toward the left it will carry with it the tie-rod connection between the immediate supports for the two front wheels, and will therefore cause these wheels to swing in unison with each other. If the wagon tongue or pole be attached to the steering arm, it will cause the wheels to shift about their vertical pivotal axis, whenever the pole is swung toward the right or toward the left, and at the same time the pole will transmit the pulling stresses directly to the front sill of the vehicle instead of to the axle; and consequently the axle will not be called upon to bear any of the usual stresses except those due to the load resting on the same.

One of the features of our invention has to do with the connection between the steering arm, the pole and the front sill so as to permit the pole and the steering arm to swing about a vertical axis for steering purposes, and at the same time permit the pole to swing in a vertical plane without changing the operative relation between it and the steering arm. In the particular arrangement disclosed, as best shown in Fig. 2, the steering arm extends underneath and engages with the under side of the bolster, while a second arm or plate 27 overlies the top of the sill just above the steering arm and extends forwardly across the rear half of the latter. A bolt 28 extends vertically through the steering arm, the bolster and the top plate 27. It is desirable that provision be made to take up wear in this joint and to this end we have placed underneath the head of the bolt a cone-shaped bearing block 29, and underneath the nut on the other end of the bolt, a cone-shaped bearing block 30; these blocks fitting complementary bearing seats in the members 25 and 27, respectively. In order better to distribute the pulling stresses at the sill, the bolster may have a hub-like part 31 extending forward through the web of the sill and into a cylindrical opening in the upper cone 30. The small ends of the cones are directed towards each other and are provided with a few relatively narrow lugs or projections 32, as best shown in Fig. 7. The lugs on the bottom cone bear against the under side of the bolster, while the lugs on the upper cone bear against the top surface of the front sill. As wear occurs, the lugs may be shortened quickly and conveniently by simply filing or chipping them. In this way the cones are permitted to be drawn farther into the bearing openings in the members 25 and 27, thus compensating for wear.

Between the front end of the plate or strap 27 and the underlying steering arm is arranged a block 34 which may conveniently be held in place by means of bolts 35 passing vertically through the members 25, 34 and 27. A bolt 36 extends transversely through the block 34, parallel with the axle. The block 34 is provided on opposite sides with sleeve-like projections or bushings 37 fixed thereto, surrounding the bolt 36, and provided at their inner ends with comparatively wide flanges or enlargements 38. On the rear end of the wagon tongue or pole 39 are fixed two castings or arms 40, 40 projecting rearwardly from the tongue or pole and having in such projecting portions openings large enough to receive the sleeves or bushings 37; the sides of the castings engaging with the flanges 38 which offer large bearing surfaces. In order to compensate for wear, we prefer not to have the bearings directly between the bushings and the members 40, since, by using conical bearing members such as those heretofore described, compensation for wear may readily be made. Therefore the holes in the members 40 are made conical, as indicated at 41, and larger at their small ends than the diameter of the bushing. Cone-shaped sleeves or blocks 42 are placed in these openings or holes and around the bushings. Washers 43 are arranged between the cone-shaped members 42 and the head and the nut on the bolt 36 so that the head

and the nut need not be made unduly large. When this particular joint becomes more or less worn, the lugs on the cones are shortened in the manner heretofore explained in connection with the other pivotal joint for the pole, so as to permit the cones to take up the wear.

It will thus be seen that the pulling stresses are imposed directly on the frame-work of the vehicle body and are not transmitted through the axle. In order to help hold the sill in place and prevent it from being pulled out from under the box or body, we prefer to tie it to what may be termed the rear bolster which carries the bearings for the rear axle. This construction is best shown in Figs. 1, 3 and 8. Two rods, 45 and 46, are bolted at their front ends to the front sill, conveniently by means of bolts 47, 47 passing through the sill and the ends of the underlying front bolster. These rods extend rearwardly and outwardly to brackets 48, 48 attached to the frame of the body about half way between the front and the rear. Nuts 49, on the rear ends of these rods, and lying behind the brackets 48, permit the tension on the rods to be adjusted. Two other tie rods, 50 and 51, extend rearwardly from the brackets 48 to the rear bolster 52, which has bearings 53 for the rear axle 54. The rods 50 and 51 are provided at their rear ends with eyes 55 through which pass suitable fastening means for attaching them to the rear bolster. On the front ends of the tie rods 50 and 51 are nuts 56 lying in front of the brackets 48, so that, by turning these nuts, the tension of the rods 50 and 51 may be varied.

It will thus be seen that we have produced a simple and novel front end construction for pole-drawn vehicles, in which the axle serves simply as a load-supporting member and may therefore be semi-floating in character; in which the individually-pivoted wheels may be readily aligned and kept in alignment; in which the steering is effectively accomplished by the lateral swinging of the

usual wagon pole, regardless of the angular position of the pole in a vertical plane; in which compensation for wear in the pivot joint between the pole and the vehicle body can easily be made; and in which the front sill is effectively tied to the rest of the framework of the vehicle body to avoid the possibility of pulling the front sill away from the vehicle body.

While we have illustrated and described with particularity only a single preferred form of our invention, we do not desire to be limited to the exact structural details thus illustrated and described; but intend to cover all forms and arrangements which come within the terms employed in the definitions of our invention constituting the appended claims.

We claim:

1. In combination, a vehicle body having a front sill, an axle made of two separated parallel beams lying below said sill, wheel supports on the ends of said axle, pedestals extending down from the sill between said beams, said pedestals having vertically-elongated slots therethrough, bolts passing through the axle and through said slots, and a draft device attached to the middle of said sill.

2. In combination, a vehicle body having a front sill, an axle made of two separated parallel beams lying below said sill, wheel supports on the ends of said axle, pedestals extending down from the sill between said beams, said pedestals having vertically-elongated slots therethrough, bolts passing through the axle and through said slots, aligning members fixed to said sill near the ends thereof and projecting down therefrom between the two members forming the axle, and a draft device attached to the middle of said sill.

In testimony whereof, we sign this specification.

CLARENCE C. HERMANN.
EDGAR C. LITCHFIELD.
